SEPARABLE FINGER RING

Frederick J. Kuczajda, Riverside, Ontario, Canada, and
Willis E. Angell, Warren, Mich., assignors to Fayrick
Mfg., Inc., Detroit, Mich., a corporation of Michigan

Filed Jan. 15, 1962, Ser. No. 68,308

Term of patent 14 years

(CL D45—10)

FIG. 1 is a front elevational view of a separable finger ring showing our new design, the separable parts thereof interfitted;

FIG. 2 is a side elevational view thereof;

FIG. 3 is a top plan view thereof;

FIG. 4, is a view similar to FIG. 2 but showing the ring parts in separated condition;

FIG. 5 is a top plan view thereof;

FIG. 6 is a right-side elevational view of the left hand ring part as shown in FIG. 4;

FIG. 7 is a right-side elevational view of the right hand ring part as shown in FIG. 4; and

FIG. 8 is a fragmentary left-side elevational view thereof.

The essential features of our design reside in the portions shown in full lines in the drawings.

Our ring design is characterized by the two separable parts which when interfitted display the mounting of the

one part centrally disposed over both parts thereof, as shown best in FIGS. 2 and 3.

We claim:

The ornamental design for a separable finger ring, as shown and described.
